Pentair Residential Filtration, LLC; "Water Filtration System and Method;" PCT/US14/44418; International Search Report & Written Opinion filed Jun. 26, 2014.

Primary Examiner — Robin V Webster(74) *Attorney, Agent, or Firm* — Quarles & Brady LLP(57) **CLAIM**

The ornamental design for a filter cartridge, as shown and described.

DESCRIPTION

The FIGURE is a filter cartridge showing the new design. The broken lines showing the filter cartridge are included for the purpose of illustrating environmental structure and form no part of the claimed design. The rear isometric view of the FIGURE forms no part of the claimed design.

1 Claim, 1 Drawing Sheet(56)
